UNITED STATES PATENT OFFICE.

FREDERICK C. WAPPLER, OF NEW YORK, N. Y., ASSIGNOR TO COMPREX OSCILLATOR CORPORATION, OF NEW YORK, N. Y., A CORPORATION OF NEW YORK.

APPARATUS FOR SETTING UP A VIBRATORY AIR COLUMN.

Application filed December 4, 1924. Serial No. 753,779.

The invention relates to an air compressing device which, although capable of other uses, is particularly adapted for medical purposes, for example, what is known as a penetrating massage wherein the effect is desired of a vibratory column of air. Motor driven pumps for such purposes have been produced in which the pump was connected to the motor through some form of speed reducing mechanism such as belts, gears, etc., but the rate of air impulses so obtained could not exceed about two thousand per minute as a practical matter, and furthermore such devices necessarily involve cumbersome and expensive 10 mountings to keep the parts in proper relation to each other, and counteract the detrimental effects of vibrations.

According to the present invention I employ an air pump which is direct connected to a small high speed motor, and preferably mounted directly thereon, making up a unitary and much more compact structure which preferably is flexibly supported from a suitable standard to avoid the detrimental effects 25 of vibrations and which is capable of practical operation at much higher speeds than heretofore.

The above and other objects and advantages of the invention will be in part obvious and 30 in part specifically pointed out in the description hereinafter contained, which, taken in connection with the accompanying drawings, discloses a preferred embodiment of the invention; such embodiment, however, is to be 35 considered as merely illustrative of its principles. In the drawings:

Fig. 1 is an end view of an air compressing device constructed in accordance with the invention, the air pump thereof being shown in 40 section.

Fig. 2 is a side view of the structure shown in Fig. 1 with the air pump also appearing in section.

Fig. 3 is a central sectional view showing 45 detached a valve which may be employed in connection with the air compressing device.

Fig. 4 is a plan view of the air pump shown in Figs. 1 and 2, and the adjacent end of the motor housing.

50 The illustrated type of air pump consists of a cylinder or casing 1, within which reciprocates a piston 2 having a connecting rod 3 associated therewith. As shown, the impulses of the pump are delivered through an 55 opening 4 (Fig. 1) in the cylinder head, into

which opening tapered plug 5 carrying a delivery tube 6 may be inserted when the effect is desired of a vibratory column of air. The pump is preferably provided with suitable fins 7 for air-cooling purposes. 60

To drive the pump I employ an electric motor 8 having a spindle 9 suitably journaled within the motor housing 10, and, as above stated, according to one feature of the invention the air pump is direct connected 65 to the motor so as to be driven therefrom without the interposition of speed-reducing gearing or the like.

As shown, the pump casing 1 is located at 70 one end of the motor housing 10, and is substantially radial to spindle 9. The casing 1 is also rigidly connected to and supported from the housing 10, this being accomplished in the present instance by providing flanges 11 75 on the casing which are disposed laterally of the motor hub 12, and are detachably secured to the motor housing 10 by screws 13. As shown, the projecting end of spindle 9 is provided with a collar 14 having a crank pin 15 thereon engaging the connecting rod 3, to 80 directly connect the piston of the pump with the motor.

The pump and motor therefore are assembled into a unitary structure which is exceedingly compact, and furthermore is substantially rigid as regards vibrations. It is therefore possible to operate the pump at 85 much higher speed than heretofore, the latter working satisfactorily with the motor running at from five thousand to eight thousand 90 R. P. M., as contrasted to a previously maximum allowable speed in the neighborhood of two thousand strokes per minute.

In the present embodiment of the invention the pump casing 1 is extended down to 95 enclose the protruding end of spindle 9 and associated parts, thereby providing a casing for connecting rod 3. The pump structure may also be assembled with and detached from the motor by endwise movement, the 100 connecting rod 3 being slidable along crank pin 15. In the present instance the bottom of the pump casing is closed by a removable plug 16 which may be detached to afford access to the interior of the casing for the purpose of alining the lower part of the connecting rod 3 with the crank pin 15. With the 105 parts in this position the pump structure may be slid into its proper position and the screws 13 tightened up. A washer 17 (Fig. 2) may 110

also be interposed between collar 14 and hub 12, and seated against the inner wall of casing 1 to provide a tight joint for the interior of such casing. 53

5 In the present form of the invention the plug 16 provides an oil reservoir 18 for lubricating the parts of the pump. It is not necessary that the level of the oil be as high as the connecting rod 3 in most instances, 10 since owing to the vibrations of the device at high speeds the oil will be distributed to all parts of the casing. A suitable oil hole 19 is provided in the casing 1.

15 I prefer to construct the air pump in such manner that it may be readily adjusted to produce either a vibrating column of air, as will be obtained by the structure shown in Fig. 1, or pressure or vacuum impulses. As is shown in Fig. 3, a valve member 20 may be 20 employed having a hollow plug 21 similar to the member 5 previously described, and leading to a pair of air passages which contain oppositely-acting check valves. As shown, the valve member 20 is T-shaped, and provided with arms 22 and 23 adapted to be connected to delivery tubes and respectively containing the check valves above referred to, the check valves being illustrated as having valve seats 24 within which valve members 25 are 25 slidably mounted. The valve members 25 are provided with heads 26 adapted to seat against the members 24 to close the valves, and with stops 27 at their opposite ends to limit the distance members 25 may move in 30 opening. Thus, as the valve appears in Fig. 3, vacuum or suction impulses only are permitted to pass through the arm 22 in the direction of the arrow, while pressure impulses only may pass through arm 23. Thus, by 35 connecting a tube selectively to the arms 22 and 23, the effect of vacuum or pressure impulses may be obtained as desired.

40 I also prefer to support the air compressing device above mentioned so as to cushion the effect of vibrations thereon. In the present instance the unitary structure consisting of a motor and pump, is yieldably supported from a standard having a base 28 and an upright 29 of inverted U shape, by means of the 45 springs 30 (Fig. 1). If desired, the base 28 may also be utilized to contain a speed-controlling device for the motor, a dial 31 being shown for this purpose in the present embodiment, and a flexible cable 32 extends be-

tween the motor and the base to provide current leads to the motor. 55

While a specific embodiment of the invention has been described, it will be obvious that many changes may be made therein without departing from its principles, as defined in 60 the appended claims.

I claim:

1. An apparatus for setting up a vibratory air column, comprising a motor and housing therefor, a cylinder fixed with regard to the 65 motor housing, a piston reciprocating within said cylinder and direct connected to the spindle of said motor, said cylinder having a delivery opening communicating with the cylinder space during both strokes of the piston to set up a vibratory air column, said cylinder being closed against air admission and delivery except through said above mentioned opening. 70

2. An apparatus for setting up a vibratory air column, comprising a motor and housing therefor, a pump cylinder fixedly connected to the motor housing, a piston reciprocating within said cylinder and direct connected to the spindle of said motor, said cylinder having a delivery opening communicating with the cylinder space during both strokes of the piston to set up a vibratory air column and a supporting standard, said motor and pump structure being resiliently supported from 80 said standard to permit such structure to vibrate in response to the impulses set up by the piston. 85

3. An apparatus for setting up a vibratory air column, comprising a motor and housing 90 therefor, a pump cylinder fixedly connected to the motor housing, a piston reciprocating within said cylinder and direct connected to the spindle of said motor, said cylinder having a delivery opening communicating with the cylinder space during both strokes of the piston to set up a vibratory air column and a supporting standard comprising a base member and an upright mounted thereon, said motor and pump structure being resiliently suspended from 95 said upright to permit said structure to vibrate in response to the impulses set up by the piston. 100

In testimony that I claim the foregoing, I have hereunto set my hand this 21st day of November, 1924. 105

FREDERICK C. WAPPLER.
